CLAIM

The ornamental design for a cutlery tool and holder, as shown and described.

DESCRIPTION

FIG. 1 is a front isometric view of the holder portion of the new design for a cutlery tool and holder;

FIG. 2 is a rear isometric view of FIG. 1;

FIG. 3 is a front view of FIG. 1;

FIG. 4 is a rear view of FIG. 1;

FIG. 5 is a top view of FIG. 1;

FIG. 6 is a bottom view of FIG. 1;

FIG. 7 is a left side view of FIG. 1;

FIG. 8 is a right side view of FIG. 1;

FIG. 9 is a front isometric view of the cutlery tool portion of the new design for a cutlery tool and holder;

FIG. 10 is a rear isometric view of FIG. 9;

FIG. 11 is a front view of FIG. 9;

FIG. 12 is a rear view of FIG. 9;

FIG. 13 is a top view of FIG. 9;

FIG. 14 is a bottom view of FIG. 9;

FIG. 15 is a left side view of FIG. 9; and,

FIG. 16 is a right side view of FIG. 9.
